UNITED STATES PATENT OFFICE.

FRANK T. WIECHERT, OF BELLEVUE, OHIO, ASSIGNOR TO THE WISE SODA APPARATUS COMPANY, OF BELLEVUE, OHIO, A CORPORATION OF OHIO.

DISPENSING APPARATUS.

1,091,554.

Specification of Letters Patent. Patented Mar. 31, 1914.

Application filed May 24, 1912, Serial No. 699,369. Renewed August 28, 1913. Serial No. 787,206.

To all whom it may concern:

Be it known that I, FRANK T. WIECHERT, a citizen of the United States, residing at Bellevue, in the county of Huron and State of Ohio, have invented certain new and useful Improvements in Dispensing Apparatus, of which the following is a specification.

My invention relates to improvements in dispensing apparatus, and more particularly to syrup-dispensing pumps, designed with special reference for use in connection with soda fountains, said pumps being preferably arranged in jars or containers and being adapted to discharge measured quantities of syrups used in connection with dispensing various drinks from such soda fountains.

The primary object of the invention is to provide a generally improved syrup dispensing pump of this class of exceedingly simple, cheap and efficient construction, having its parts so arranged and disposed relative to each other that the liability to disarrangement or breakage of the parts is reduced to a minimum.

25 A further object is to improve and simplify the construction and arrangement of the plunger mechanism and means for regulating and adjusting the stroke of the plunger or pump whereby to regulate the amount of liquid to be dispensed with each working impulse of the plunger or pump as desired.

With the above mentioned and other ends in view, the invention consists in the novel 35 construction, arrangement, and combination of parts, hereinafter described, illustrated in one of its embodiments in the accompanying drawings, and particularly pointed out in the appended claims.

40 Referring to the drawings forming a part of this specification, Figure 1, is a side elevation of a dispensing pump constructed in accordance with this invention. Fig. 2, a central vertical sectional view of the same.

45 Fig. 3, a cross sectional view taken on line 3—3 of Fig. 2. Fig. 4, a cross sectional view taken on line 4—4 of Fig. 2.

Similar numerals of reference designate like parts throughout all the figures of the 50 drawings.

The improved dispensing pump comprises a stationary pump body 1, provided at its top with a plunger guide housing 2, and at its bottom with a measuring cup or syrup receptacle 3, the latter forming the measur-

ing chamber 3^a for measured quantities of syrup to be dispensed, said measuring chamber communicating at one side with a discharge conduit 1^a, the latter, in the present instance, being forped by means of a conduit stem 1^b of the pump body connecting the guide housing 2, and measuring cup 3.

The upper portion of the pump is adapted to be connected to the usual syrup jar or container cover 4, by means of a flanged cap 5, terminating in a discharge spout or bib 5^a, said cap 5, being provided with a threaded opening taking over and threaded upon a threaded stem portion 1^b, of the pump body, said threaded stem portion 1^b, extending through a suitable opening in the syrup jar or container cover 4, and forming a continuation of the discharge conduit 1^a, communicating with the interior of the discharge spout 5^a.

25 The plunger head 6, is adapted to coöperate within the measuring cup 3, the syrup or liquid to be dispensed being adapted to pass into the measuring chamber 3^a, of the cup or syrup receptacle through liquid or syrup inlet openings 3^b, when the plunger 75 head is in its elevated position, as shown in the drawings.

As a means for operating the plunger head as well as regulating the stroke of the latter, said plunger head is connected to a plunger stem 6^a, said plunger stem extending through the guide housing 2, and being provided at its top with a threaded portion 6^b, carrying a regulating sleeve 7, and a coöperating regulating handle or knob 8, both the sleeve 7 and the knob 8 being threaded upon the threaded stem 6^b, the knob 8 operating to lock the regulating sleeve 7, in any desired adjusted position, whereby the downward thrust or throw of the plunger head 6, in the 80 measuring chamber 3^a, may be regulated to regulate the amount of liquid or syrup dispensed from said measuring chamber with each working impulse of the pump handle or plunger stem. A guide stop 9, which 85 guides the plunger stem and limits its upward movement is removably mounted in the lower end of the plunger housing 2, said guide stop, in the present instance, being in the form of a bushing nut, threaded in the 90 present instance, in a guide sleeve 2^a, within the guide housing, said guide sleeve 2^a, terminating at its top in a flanged portion 2^b, taking over the marginal edges of a corresponding opening in the cap 5, carrying the 95

100

discharge spout 5^a. As a means for returning the plunger stem 6^a and plunger head 6, after each working impulse, a plunger spring 10, is interposed between the guide 5 stop or bushing 9, and the regulating sleeve 7, and surrounding the plunger stem portion 6^b, as shown most clearly in Fig. 2, of the drawings.

From the foregoing description, taken in 10 connection with the accompanying drawings, the operation and advantages of my invention will be readily understood.

Having thus described one of the embodiments of my invention, what I claim and desire 15. to secure by Letters Patent is,—

1. In a dispensing apparatus, a pump body provided with a discharge conduit terminating in a threaded stem portion and having an offset head provided with a plunger guide opening, and a cap having a discharge spout, the base of the latter being threaded on said threaded stem portion and said cap being provided with an opening in alignment with said plunger guide opening.

2. A dispensing apparatus, comprising a stationary pump body including a discharge conduit stem provided with a plunger guide housing and a measuring cup, a plunger and plunger stem mounted in said cup and housing, a regulating sleeve on said stem and within said housing, and a regulating handle on said stem in coöperative locking relation to said sleeve.

3. A dispensing apparatus, comprising a 35 pump body provided with a plunger housing at one end and a measuring cup at the other, a plunger and plunger stem, a regulating member on said stem, a regulating handle on said stem adapted to lock 40 said regulating member in adjusted position, a guide stop removably carried by said housing, and a plunger spring interposed between said guide stop and said regulating member.

4. A dispensing apparatus, comprising a 45 pump body having a conduit stem provided with an offset guide housing and a communicating measuring cup, a plunger mounted in said measuring cup and provided with a threaded stem extending through said offset guide housing, a regulating member adjustably mounted on said stem, a plunger handle adjustably mounted on said stem and adapted to lock said regulating member in adjusted position, a guide 50 member removably mounted in said guide housing, and a spring interposed between said guide member and said regulating member.

5. In a dispensing apparatus, a stationary 60 pump body having a discharge conduit terminating in a threaded stem portion and a plunger stem opening, a cap threaded on said threaded stem portion and provided with an opening in alignment with said 65 plunger stem opening, a guide sleeve mounted in said plunger stem and cap openings, a plunger stem extending through said guide sleeve, a regulating sleeve on said plunger stem, a guide stop at the lower end of said 70 guide sleeve, and a plunger spring interposed between said guide stop and said regulating member.

6. In a dispensing apparatus, a pump 75 body provided with a discharge conduit terminating in a threaded stem portion and provided with a head having a guide stem opening, a cap provided with a discharge spout threaded on said threaded stem portion and having a guide opening in alignment with said guide stem opening, a container cover interposed between said cap and head and provided with an opening receiving said threaded stem portion and a second opening in alignment with said guide 80 stem opening and the opening of said cap, and a guide sleeve extending through the opening of said cap and said guide stem opening.

7. In a dispensing apparatus, a pump 90 body having a head provided on one side with a discharge conduit terminating in a threaded stem portion and at the other with a plunger guide opening, a cap provided with a discharge spout threaded on said threaded 95 stem portion, said cap having an opening in alignment with said plunger guide opening, a flanged guide sleeve mounted in said last mentioned opening and extending through said plunger guide opening, a bushing nut threaded in the lower end of said guide sleeve, a plunger stem extending through said bushing nut and said guide sleeve and provided with a threaded stem portion, a regulating member within said sleeve and adjustably mounted on said threaded stem portion, a handle knob on said threaded stem portion and adapted to lock said threaded member in adjusted position, and a plunger spring interposed between said 100 bushing nut and said regulating member.

In testimony whereof I have affixed my signature in presence of two witnesses.

FRANK T. WIECHERT.
